HEEL SEAT FITTING MACHINE

Fred L. MacKenzie, Beverly, Mass., assignor to
 United Shoe Machinery Corporation, Paterson,
 N. J., a corporation of New Jersey

Application December 20, 1934, Serial No. 758,470

27 Claims. (Cl. 12—31.5)

This invention relates to the manufacture of shoes and is illustrated as embodied in a heel-seat fitting machine.

It has been proposed to position a sole, attached to a shoe upper, lengthwise in a heel-seat fitting machine by the use of a back gage against which the rear end of the shoe upper is forced and the movement of which, under pressure of the shoe upper, is limited by a measuring stop. 5
 In order accurately to position the stop it is sometimes the practice operatively to connect the stop with a movable abutment of a gage which measures the length of the attaching face of a heel to be attached to the shoe upper. In order 10
 to position the heel in the heel gage the operator places the heel, attaching face downwardly, upon a table and then swings a hand lever which slides the abutment over the table into engagement with the rear end of the rim of the attaching face of the heel and forces the breast of the heel against a stationary abutment of the gage, connections being provided to position the measuring stop in accordance with the position 15
 of the slideable heel-engaging abutment. Such a 20
 construction is disclosed in United States Letters Patent No. 1,980,371, granted November 13, 1934 on an application filed in the name of Earl A. Bessom.

In order to expedite the positioning of a heel 30
 in the heel gage and in accordance with a feature of this invention the illustrated machine comprises a gage provided with a movable abutment for measuring a heel, a movable back gage constructed and arranged to be engaged by the 35
 rear end of a shoe upper, and mechanism operable under pressure of the heel against the abutment constructed and arranged to determine the operative position of the movable back gage in accordance with the length of the heel.

In the illustrated construction the mechanism 40
 which is operable under pressure of the heel against the movable abutment of the heel gage comprises a stop which limits the rearward movement of the back gage. The stop, which is 45
 mounted for movement about an axis, is provided with a spiral face against which a pivotally mounted block of the back gage is forced by the shoe upper. The mechanism for operatively connecting the stop and the movable abutment of 50
 the heel gage is so constructed and arranged that the operator by forcing a heel against the abutment may rotate the stop to its adjusted position without straining the heel. The movable abutment, which is engaged by the rear end of 55
 the rim of the attaching face of the heel, is nor-

mally urged toward a stationary abutment of the heel gage until a stud carried by the stop engages a fixed member. To reduce the tendency of the stop being moved about its axis under pressure of the back gage the axis of the stop is arranged substantially in alignment with the path of movement of the back gage. In order to insure that the heel measured by the movable abutment shall be securely forced against the table of the heel gage and in accordance with a further feature of this invention the illustrated machine is provided with a heel holddown. 5

In order to remove the chip which is trimmed from the heel-seat portion of the sole and is left upon a sole-supporting plate of the machine, the illustrated machine, in accordance with another feature of the invention, is provided with an ejector bar which is mounted for movement in a predetermined path and is supported by and in engagement with the sole-engaging surface of the plate, the bar being mounted for movement about an axis disposed at a substantial angle to said path thereby to permit the bar to engage the sole-supporting surface throughout its travel. The ejector bar is operated through a spring and, 15
 in order to insure that the chip is pushed from the sole-supporting plate instead of being thrown from the same, cushioning means which opposes the spring is provided. 20
 25

These and other features of the invention, including certain details of construction and combinations of parts, will be described as embodied in an illustrated machine and pointed out in the appended claims. 30

In the drawings, 35

Fig. 1 is a side elevational view of a portion of the illustrated machine, parts of which have been broken away;

Fig. 2 is a front elevational view of the machine illustrated in Fig. 1, the mechanism for forming heel-breast receiving shoulders upon the sole having been broken away; 40

Fig. 3 is a plan view of the heel gage and the shoe positioning mechanism of the illustrated machine; 45

Fig. 4 is a perspective view of portions of the mechanism shown in Fig. 3, parts of the mechanism being broken away in order better to show the construction thereof;

Fig. 5 is a sectional view of the shoe positioning mechanism of the machine taken along line V—V of Fig. 3; 50

Fig. 6 is a perspective view showing in detail the construction of the chip ejector and a carrier therefor; 55

Fig. 7 shows in perspective a latch for temporarily holding an ejector-operating lever in a forward position until it has been released by a sole-distorting plunger of the machine; and

- 5 Fig. 8 is a perspective view of a heel positioned in a heel gage equipped with a holddown.

The invention is illustrated with reference to the heel-seat fitting machine disclosed in United States Letters Patent No. 1,980,371, above referred to, and is provided with a crease plate 20 having a U-shaped opening 22 (Figs. 4 and 6) and formed and arranged to be positioned between a shoe upper and the heel-seat portion of a sole attached to the shoe upper. In order to position the sole widthwise and lengthwise of the crease plate 20 the machine is provided with a bifurcated centralizing slide 24 and a back slide 26 constructed and arranged to engage the sides and the rear end respectively of the counter portion of the shoe upper. The construction and operation of the slides 24, 26 will later be described in detail.

After the heel-seat portion of the sole has been positioned upon the crease plate 20 a U-shaped clamp 28 is lowered to force the margin of the heel seat portion of the sole against a beveled crease plate surface 30 (Figs. 4 and 6) surrounding the U-shaped opening 22. While the margin of the heel seat portion of the sole is clamped against the crease plate 20 a bulger 32 (Fig. 2) is lowered to force the central part of the heel-seat portion of the sole through the opening 22 and below a bottom planar face 34 (Fig. 5) of the crease plate.

35 The clamping and the bulging operations above described are performed by lowering a rod 36 (Fig. 1), the bottom end of which is connected to a foot treadle (not shown). The upper end of the rod is pivotally secured to a rocker arm 38 which is mounted upon the main frame 40 of the machine and operates another rocker arm 42 through the provision of a connecting link 44 having a depending extension 46. The depending extension 46 is used to actuate a chip ejector, as will later be explained in detail. The forward end of the rocker arm 42 is pivotally connected through a link 48 and a coupling 50 to a plunger rod 52 to the bottom of which the bulger 32 is secured.

50 The U-shaped presser member 28 is supported within a housing 54 (Figs. 1 and 2), an upper extension 56 of which engages a spring 58 enclosed within an inverted casing 60 secured for movement with the rod 52. The housing 54 is raised 55 with the bulger 32 away from the work by a flange (not shown) carried by the plunger rod 52. When the operator first depresses the treadle the presser member 28 is lowered under foot pressure to clamp the margin of the heel seat portion of the sole against the beveled surface 30 of the crease plate 32. Further depression of the treadle causes a power-operated cam (not shown) to lower the rod 36, thereby to force the bulger 32 downwardly until the casing 60 engages a boss 62 of the main frame. When the casing 60 engages the boss 62 the lower sole-engaging face of the bulger 32 is located slightly above the lower face 34 (Fig. 5) of the crease plate 20. Any further movement of the treadle causes a safety 65 spring 64 (Fig. 1) carried by the rod 36 to be compressed.

70 After the heel-seat portion of the sole of the shoe has been properly distorted the heel-seat reducing cutter 66 (Figs. 4 and 5), which is moved forwardly of the crease plate 20 and has a

straight cutting edge 68 in engagement with the lower face 34 of the crease plate, trims the margin of the heel seat portion of the sole by a beveling cut.

Heel-breast receiving shoulders are formed upon the sole by shoulder-forming cutters 70 (Fig. 5) carried by a cutter carrier 72 which is adjustably secured to a slide 74 mounted for reciprocation along a guideway 76.

10 The heel-seat reducing cutter 66 is adjustably secured to a cutter carrier 71 (Fig. 5) connected by a screw 73 to a slide 78 (Figs. 1 and 5) movable forwardly and rearwardly of the machine along a guideway 80 of the main frame 40. The slide 78 is operated by a bell-crank lever 82 pinned to a shaft 84 mounted upon a bearing 86 supported by the main frame, the lever being connected to the slide 78 by a link 88 and to an operating cam (not shown) by a rod 90. The shoulder-forming cutters 70 may be operated 15 either before or after the heel-seat portion of the sole has been reduced.

20 The heel-seat reducing cutters 66 and the shoulder-forming cutters 70 are automatically operated by power when a lever (not shown) is tripped by the treadle. As above stated, the mechanism for clamping and distorting the heel-seat portion of the sole as well as the mechanism for trimming the sole is clearly illustrated and described in United States Letters Patent No. 1,980,371, which should be referred to for a complete understanding of the construction and operation of the machine.

25 Rearward movement of the centralizing slide 24 and the back slide 26 under pressure of the shoe is limited by a stop 92 through mechanism which will be described later, the stop 92 being rotated to a predetermined position in accordance with the size of a heel 94 (Fig. 8) positioned in a heel gage. The mechanism for positioning 30 the shoe lengthwise in the machine will be referred to as a back gage and the mechanism for positioning the shoe widthwise will be referred to as a centralizing gage. In order to reduce to a minimum lost motion on the part of the operator it is desirable to insert the heel in the heel gage under pressure of the heel, the operator then having only to pick up the heel which is to be applied to the shoe and to set it in the gage. Accordingly, an abutment 96, which is mounted 35 for sliding movement along a guideway 98 (Fig. 3), is engaged by the rear end of the rim of the attaching face of the heel and is pushed rearwardly under pressure of the heel until the heel may be placed attaching face downwardly upon a 40 table 102 between the sliding abutment 96 and a stationary breast plate or abutment 100. The sliding abutment 96 is normally urged toward the breast plate 100 by a spring 104, the arrangement being such that when the heel has been 45 placed attaching face downwardly upon the table 102 the breast of the heel is forced against the breast plate 100 by the sliding abutment 96 and is thus properly oriented upon the table. The heel is thus clamped between the forward and 50 rear abutments 96, 100 and is measured lengthwise in the heel gage.

55 The back slide 26 is movable forwardly and rearwardly of the machine along a straight groove 106 (Fig. 4) formed in the lower surface of a 60 stop plate 108 which is mounted for movement in a pair of opposed rectilinear guideways 110 of the main frame. The centralizing slide 24, the work-engaging faces 112 of which are positioned 65 at equal distances from a median plane 114 (Fig. 75

3), is also mounted for movement along a pair of opposed guideways 116 arranged parallel to and positioned just above the respective guideways 110. The centralizing slide 24 is normally urged forwardly of the machine against an up-standing lug 118 of the stop plate 108 by a spring 120 enclosed within a recess of the centralizing slide and engaging the forward portion of a rod 122 which enters the recess. The rear end of the rod 122 engages a bracket 124 (Fig. 3) secured to the main frame by screws 126.

The back slide 26 is provided with an elongated slot 128 (Figs. 4 and 5) and is normally urged forwardly of the stop plate 108 by a spring 130 until a shoulder of the back slide engages the rear face of the stop plate 108. Extending through the elongated slide 128 is a block 132 supported by a screw 134 in threaded relation with the stop plate 108 and surrounded by a sleeve 136 which passes through an arcuate opening 138 (Fig. 4) formed in the block 132. A depending pin 140 is secured to the stop plate 108 and enters a circular recess of the block 132, the arrangement being such that the block 132 may be swung relatively to the stop plate 108 about the pin 140 within limits determined by the arcuate opening 138. A depending rod 142 is carried by the block 132 and is arranged to engage the main frame 40 to limit forward movement of the block. The block 132 is provided at its rear end with a concave cylindrical surface covered by a piece of facing material 144 having a relatively high coefficient of friction and constructed and arranged to engage the operating face 146 of the stop 92, which face has the form of a spiral of Archimedes. It will thus be clear from the foregoing that the centralizing slide 24 is normally urged forwardly of the machine by the spring 120 and forces the stop plate 108 forwardly until the rod 142 carried by the block 132 engages the main frame 40. As above stated, the back slide 26 is normally positioned forwardly of the stop plate 108 by the spring 130. When the shoe is presented to the machine rear end first and bottom side up, the sides of the counter portion of the shoe upper engage the respective work-engaging faces 112 of the centralizing slide 24 to position the shoe widthwise and as the shoe is moved rearwardly, the rear end of the counter portion of the shoe upper engages the back slide 26 and forces the same, together with the centralizing slide 24, rearwardly until the facing material 144, which may be made of leather, engages the spiral face 146 of the stop 92.

The stop 92 is mounted for rotary movement about a bearing 148 secured to the frame of the machine, the axis of the bearing lying in the plane 114. By providing the stop 92 with a face 146 having the form of a spiral of Archimedes it will be clear that for equal angles of swing of the stop, the face 146 of the stop crossing the plane 114 will move equal distances forwardly and rearwardly of the machine.

As above stated, it is desirable that the stop 92 shall be swung to the proper position under the rearward pressure of the heel against the sliding abutment 96, without exerting too great a pressure upon the heel. Accordingly, the stop 92 is rotated by a gear 150 (Fig. 3) which is pinned to the stop 92 and meshes with a geared segment 152 provided with a hub portion 154 which straddles a boss 156 (Fig. 1) of the main frame and is mounted upon a shaft 153 rigidly supported by the boss. The hub portion 154 of the geared segment 152 is provided with an extension 158

(Fig. 3) pivotally connected to an angular arm 160 which is adjustably secured to the sliding abutment 96 of the heel gage by a screw 162. Since the abutment 96 is connected directly to the extension 158 the guideway 98 along which the abutment 96 slides is slightly wider than the abutment to permit the same to be shifted laterally a small amount.

The stationary breast plate 100 (Fig. 8) is held against the table by a screw 164 which passes through an opening in the plate and is in threaded engagement with the table 102. The breast plate 100 comprises a flat face 166 for engaging the projecting lip or the breast of a Louis heel and a convex face 168 inclined to the table and constructed and arranged to engage the concave breast of a Cuban heel. The bottom side of the stationary plate 100 is provided with a V-shaped recess 170 within which a spring-pressed plunger (not shown) engages. The stationary plate 100 may be readily turned in accordance with the type of work being operated upon, the spring-pressed plunger serving properly to locate the plate 100 and to retain the same in operating position. When the heel is removed from the heel gage the sliding abutment 96 is forced forwardly by the torsional spring 104 until a pin 172 (Fig. 3) carried by the stop 92 engages a fixed pin or member 174 secured to the main frame 40, the upper end of the spring being secured to the hub 154 of the geared segment 152 and the lower end of the spring being secured to a flange 176 of the shaft 153.

Friction between the parts of the mechanism for setting the stop 92 in the proper position is reduced to a minimum so that excessive pressure is not exerted upon the heel being placed in the gage. The mechanism connecting the sliding abutment 96 with the stop 92 is so connected and arranged that the effective portion of the spiral face 146 moves forwardly or rearwardly with and to the same extent as the sliding abutment 96.

In order that the operator may ascertain at a glance when the block 132 has been forced against the spiral surface 146 of the stop 92, a laterally extending bar 178 (Fig. 3) is secured to the rear end of the back slide 26 and carries at its outer end an adjustable indicator rod 180 slidably supported in the frame of the machine and disposed in parallel relation to another rod 182 which is secured to the angular arm 160. As illustrated in Fig. 3 the rod 180 extends forwardly of the rod 182 when there is no work in the machine. When a shoe has forced the block 132 against the stop 92 the forward ends of the respective rods 180, 182 are in alignment.

It will be noted that since the axis about which the stop 92 is rotated is located in the plane 114 there is little tendency for the rearward pressure of the shoe against the back slide 26 to turn the stop about its axis.

After the operator has placed the heel 94 attaching face downwardly upon the table 102 it is customary to release the heel and to permit the same to be forced forwardly under pressure of the spring 104 until the breast of the heel engages the stationary plate 100. It has been found by experience that the weight of the mechanism connecting the sliding abutment 96 and the stop 92 should be reduced to a minimum in order that the heel shall not be injured as it is clamped in position. Accordingly, the stop 92 and various other parts of the stop-operating mechanism are preferably made of aluminum.

Since the face 146 of the stop 92 has the form

of a spiral of Archimedes it will be clear that if sufficient pressure is exerted against the face, and if there is substantially no friction between the block 132 and such face, the stop 92 is likely to 5 swing even though the axis about which the stop is rotated is included in the vertical plane 114. Moreover, in order that the face 146 of the stop 92 shall not be dented it is desirable that the stop-engaging face 146 of the block 132 shall be made 10 of material softer than aluminum. It has been found by experience that when the rear concave cylindrical surface of the block 132 is covered with leather facing material 144 satisfactory results are obtained, the friction between the block and 15 the face 146 being sufficient to prevent the stop from turning under rearward pressure of the block. The radius of curvature of the stop-engaging face 146 of the block 132 is such that there is substantially line contact between the 20 block and the lowest portion of the spiral face 146 and there is surface contact between the block and an intermediate portion of such face. Only the ends of the stop-engaging face 146 of the block 132 engage the highest portion of the operating 25 face 146, the block being pivotally mounted to permit such engagement and also to permit the stop-engaging face of the block to be in surface engagement with the intermediate portion of the face 146. The slight error due to the block 30 having line surface and two-point contact with different portions of the face 146 of the stop 92 is so slight that it may be disregarded. It will be noted that the error would be greater if the block 132 were not permitted to swing about the pin 35 140, as above described.

In order to position the shoe in the machine the operator places the heel to be attached to the shoe in the heel gage by forcing the rear end of the attaching face of the heel against the sliding 40 abutment 96 and after placing the attaching face of the heel downwardly upon the table, the abutment 96 under pressure of the spring 104 forces the breast of the heel against the stationary plate 100. Forward movement of the abutment 96 through mechanism above described causes the stop 92 to swing to a predetermined position. The shoe, bottom side up and rear end first, is then moved rearwardly of the machine, the side of the counter portion of the shoe first engaging 45 the faces 112 of the centralizing slide 24. As the centralizing slide 24 is moved rearwardly, the rear end of the counter portion of the shoe upper is forced against the back slide 26 and moves the same rearwardly with the centralizing slide 24 until the block 32 is forced against the spiral face 50 146 of the stop 92. The operator then glances at the rods 180, 182 to insure that the same are in alignment.

In order to remove from the machine a U-shaped chip which is left upon the crease plate 20 after the heel-seat portion of the sole has been trimmed by the heel-seat reducing cutter 66 and the shoulder-forming cutters 70, the illustrated machine is provided with an ejector bar 184 55 (Figs. 2 and 6) which is constructed and arranged to engage the crease plate 20 as it moves over the same. The ejector bar 184, which is slightly curved in accordance with the opening 22 of the crease plate, is trunnioned upon a slide 186 (Fig. 6) movable forwardly and rearwardly along a guide 188. Extending from the slide 186 is a pin 190 constructed and arranged to engage within an elongated slot 192 (Fig. 1) of an operating arm 194 which is mounted upon a shaft 196 carried by the main frame and has extending from

its upper end a lug 198 arranged to engage a stop 200. A spring 202 normally retains the ejector bar 184 rearwardly of the sole-supporting portion of the crease plate 20. The upper end of the operating arm 194 is also provided with a forward lug 204 which is constructed and arranged to be grasped by a hook end 206 of a reciprocating lever 208 in order to swing the operating arm 194 in a counterclockwise direction (Fig. 1). 10

The ejector bar 184 is normally supported by the crease plate 20. When the crease plate 20, however, is removed from the machine after pulling a plunger-pin 210 (Fig. 6) from engagement within a recess of the crease plate, the bar 15 184 is supported by a bifurcated lug 212 of an arm 214. From the foregoing it will be clear that the ejector bar 184, unless moved forwardly by the reciprocating lever 208, is held rearwardly of the sole-supporting portion of the crease plate 20 by the spring 202. It is necessary to raise the presser member 28 and the bulger 32 away from the crease plate 20 before operating the ejector bar 184.

The hook end 206 of the lever 208 is moved 25 forwardly of the lug 204 of the operating arm 194 during forward movement of the heel-seat reducing cutter 66 but is not released until after the presser member 28 and the bulger 32 have moved out of the path of movement of the ejector bar 184. The lever 208 is provided with a bottom cam surface 214 (Fig. 1) which engages a roll 216 positioned in a notch of the main frame, the lever 208 being pivotally secured at its rear end to a piston head 218. A piston 220 to which the head 218 is secured is constructed and arranged for sliding movement in a cylinder 222. The purpose of such a construction will be explained later. A coiled spring 224, opposite ends of which engage pins 226 and 228 of the lever 208 and the piston head 218, respectively, at all times retains the cam surface 214 of the lever 208 in engagement with the roll 216. A projecting portion of the cam surface 214 of the lever 208 causes the same to be raised when in a rearward position 30 35 as illustrated in Fig. 1.

In order to move the lever 208 forwardly, the cutter-operating slide 78 is provided with a laterally projecting flange 230 which upon forward movement of the slide, engages a depending portion 232 of the piston head 218 and forces the same, together with the lever 208, forwardly of the machine against the pressure of a strong spring 234. When the lever 208 has been moved forwardly of the lug 204 the hook end 206 of the lever drops into lowered position in front of the lug. When the piston head 218 moves forwardly a trip lever 236 (Fig. 7) which is pivotally mounted upon the main frame and has its front end normally forced downwardly by a spring 238, engages the rear part of the piston head 218 and temporarily holds the reciprocating lever 208 in a forward position. 50 55 60

When the presser member 28 and the bulger 32 have been raised a predetermined distance about 65 the crease plate 20, the depending portion 46 (Fig. 1) of the link 44 swings the trip lever 236 against the pressure of the spring 238 and causes the lever 208, forced rearwardly by the spring 234, to swing the operating arm 194 in a counterclockwise direction, thereby to move the ejector bar 184 forwardly across the crease plate 20. As the depending portion of the cam surface 214 of the lever 208 rides up the roll 216, the hook end 206 of the lever slides off the lug 204, and the oper- 70 75 75

ating arm 194, urged by the spring 202, moves in a clockwise direction until stopped by engagement of the lug 198 with the stop 200. The ejector arm 194 is thus moved rearwardly of the sole-
5 supporting surface of the crease plate 20.

In order to avoid flinging the chip from the crease plate 20, the cylinder 222 is provided with a rear head 240 comprising an inlet valve 242 through which air is sucked into the cylinder
10 when the piston 220 is moved to the right, and an outward valve 244 which restricts the passage of air from the inside of the cylinder as the piston is moved rearwardly under pressure of the spring 234. Such a construction provides a cushioning effect which insures that the chip is pushed slowly from the plate into a container instead of being thrown from the crease plate
15 20.

Because of the angle which the face 168 (Fig. 20) 8) of the stationary plate 100 forms with the heel-supporting surface of the table 102, the heel is sometimes lifted at its forward end under pressure of the sliding abutment 96 and accordingly the face 168 may be faced with material which
25 will tend to prevent the forward end of the heel from being lifted from the plate. To insure, however, that the heel is held securely against the table 102, a holddown 246 which engages the tread end of the heel may be provided. In the
30 illustrated construction the holddown 246 which carries a rubber roll 248 is mounted for swinging movement upon a bracket 252 secured to the table 102 and is normally urged toward the table 102 by a coil spring 250. A guide 254 is carried
35 by the bracket 252 and is constructed and arranged to receive a slide 256 which is normally urged forwardly by a spring 258 to cause a pawl 260 formed integrally with the slide to engage a serrated portion 262 formed at the rear end of
40 the holddown 246. Mounted upon the forward end of the slide 256 is a roll 264 which is engaged by the back of the heel to force the slide 256 rearwardly thereby to cause the pawl 260 to be moved away from the serrated portion and to
45 permit the holddown 246 to force the heel against the table 102. When the heel is removed from the heel gage the pawl 260 engages the serrated portion 262 before the heel is moved away from the
50 holddown 246 and thus limits the downward movement of the holddown.

Having described the invention, what I claim as new and desire to secure by Letters Patent of the United States is:

1. In a heel-seat fitting machine, a gage comprising stationary and movable abutments for measuring a heel, a movable back gage constructed and arranged for engagement with the rear end of a shoe to position the shoe in the machine, and mechanism operable by pressure of the heel
55 against said movable abutment constructed and arranged to determine the operative position of the movable back gage in accordance with the size of the heel.

2. In a heel-seat fitting machine, a gage comprising stationary and movable abutments for measuring a heel, an adjustable stop, a back gage constructed and arranged for engagement with the rear end of a shoe and movable under pressure of the same until it engages said stop, and
65 mechanism operable under pressure of a heel against said movable abutment constructed and arranged to swing the stop to a predetermined position in accordance with the size of the heel.

3. In a heel-seat fitting machine, a gage comprising a movable abutment constructed and ar-

ranged to measure a heel, an adjustable stop, a back gage constructed and arranged to engage the rear end of a shoe and movable under pressure of the shoe until it engages said stop, and mechanism operable under pressure of a heel
5 against said movable abutment constructed and arranged to move the stop and to set the same in a predetermined position in accordance with the size of the heel.

4. In a heel-seat fitting machine, a heel gage 10 comprising a movable member for engaging a heel, a back gage constructed and arranged to engage the rear end of a shoe and movable in a rectilinear path to position the same lengthwise, a stop for the back gage rotatable about an 15 axis which is disposed at a substantial angle to the path of movement of the back gage and is positioned substantially in alignment with said path, and mechanism for positioning the stop in accordance with the position of the heel.
20

5. In a heel-seat fitting machine, a gage comprising stationary and movable abutments for measuring a heel lengthwise, a stop provided with a spiral face, means including said movable abutment operated by pressure of a heel for rotating the stop to a predetermined position, and a back gage movable against said face and constructed and arranged to position the shoe lengthwise in the machine.
25

6. In a heel-seat fitting machine, a rotatable 30 stop, means operated by pressure of a heel for rotating the stop to a predetermined position, a back gage, and resilient mechanism for normally maintaining the back gage out of contact with the stop, said back gage being movable against 35 the stop under pressure of the shoe to position the shoe lengthwise in the machine.

7. In a heel-seat fitting machine, a gage comprising stationary and movable abutments constructed and arranged to measure the attaching 40 face of a heel lengthwise, a rotatable stop, a back gage movable toward and away from the stop under pressure of a shoe upper to position a sole attached to the shoe upper lengthwise, mechanism constructed and arranged to connect the stop and the movable abutment, a fixed member, and resilient means for normally urging the movable abutment toward said stationary abutment until limited by said fixed member, said mechanism being constructed and arranged to cause the movable abutment under pressure of the heel to swing the stop to a predetermined 45 position in accordance with a heel in the heel gage.

8. In a heel-seat fitting machine, a gage comprising stationary and movable abutments constructed and arranged to measure the attaching face of a heel lengthwise, a rotatable stop, a back gage movable toward and away from said stop under pressure of a shoe upper to position a sole 60 attached to the shoe upper lengthwise, mechanism constructed and arranged to connect the stop and the movable abutment, a fixed member, a spring for normally urging the movable abutment toward said stationary abutment until limited by said member, said mechanism being constructed and arranged to cause the movable abutment under pressure of the heel to swing the stop to a predetermined position in accordance with a heel in the heel gage, and means 65 for varying the tension of the spring thereby to vary the force required to cause the abutment to position said stop.
70

9. In a heel-seat fitting machine, a support for the heel-seat portion of a sole attached to
75

- a shoe upper, a measuring stop provided with a face having the general shape of a spiral of Archimedes, a back gage movable under pressure of the shoe upper to a predetermined position determined by said stop thereby to position the heel-seat portion of the sole lengthwise upon the support, a heel gage comprising a movable member for measuring a heel lengthwise, and mechanism for swinging the stop in accordance with the setting of the movable member.
10. In a heel-seat fitting machine, a plate for supporting the heel-seat portion of a sole secured to a shoe upper, a back gage for positioning the sole lengthwise upon the plate, a heel gage comprising stationary and movable abutments, a stop provided with a spiral face, mechanism constructed and arranged to connect the movable abutment with the stop, a resilient member for normally urging the movable abutment toward the stationary abutment, and a fixed member for limiting movement of the movable abutment under pressure of the resilient member toward said stationary abutment.
15. 11. In a heel-seat fitting machine, a plate formed and arranged to be positioned between a sole and upper of a shoe, means including a back gage for positioning the sole lengthwise of the plate, a stop provided with a spiral face against which the back gage may be forced, a spring for normally urging the back gage away from said stop, a heel gage provided with stationary and movable abutments, means including a geared segment for connecting the movable abutment with the stop, and a spring for normally urging the movable abutment toward the stationary abutment, said means being constructed and arranged to cause the stop to swing into adjusted position under pressure of a heel 40 in order to position the back gage forced by the shoe upper against the stop.
12. In a heel-seat fitting machine, a gage comprising stationary and movable abutments constructed and arranged to measure a heel, a stop, a back gage constructed and arranged to engage the rear end of a shoe and movable under pressure of the shoe until limited by said stop, mechanism operable under pressure of a heel against said movable abutment constructed and arranged to move the stop and to set the same in a predetermined position in accordance with the size of the heel, and a pair of indicators one of which is secured for movement with the back gage and the other of which is movable with the movable abutment, said indicators extending forwardly of the back gage and constructed and arranged to have their forward ends in alinement when the shoe has been properly positioned lengthwise in the machine.
13. A shoe-positioning apparatus comprising a rotatable stop provided with a spiral face, and a sliding back gage including a pivotally mounted block constructed and arranged to engage said face to limit rearward movement of the back gage.
14. In a shoe-positioning apparatus, a rotatable stop provided with a face having the general shape of a spiral of Archimedes, means for turning the stop about its axis to predetermined positions, and a back gage comprising a slide movable in a plane which includes said axis and a block which is pivotally mounted relatively to the slide and is constructed and arranged to engage the stop as the slide is moved under pressure of a shoe.

15. A shoe-positioning apparatus comprising a rotatable stop, means for turning the stop to a predetermined position, a slide, and a member mounted for movement with the slide and also mounted for swinging movement relatively to the slide, said member being constructed and arranged to engage the stop upon movement of the slide and to swing in accordance with the shape of the stop.
16. In a heel-seat fitting machine, a heel gage comprising an abutment for measuring a heel lengthwise, a support for the heel, and a hold-down constructed and arranged to engage the tread end of the heel and to force the heel against the support.
17. In a heel-seat fitting machine, a heel gage comprising a member for engaging the attaching face of a heel, means for positioning a heel relatively to said member, a clamp, and an arm operable under pressure of the heel constructed and arranged to permit the clamp to force the heel against the member.
18. In a heel-seat fitting machine, a table for engaging the attaching face of a heel, a stationary plate, a slidable abutment, a stop, a member, connections between the abutment and the stop, and resilient means for normally urging the slidable abutment over the table and toward the plate until limited by said member, said connections being constructed and arranged to permit the operator upon forcing the heel against the abutment to swing the stop against the pressure of said resilient means.
19. In a heel-seat fitting machine, a table for engaging the attaching face of a heel, a stationary plate, a sliding abutment, a spring-pressed hold-down for forcing the heel against the table, and a latch member for retaining the hold-down in a raised position, said latch member being movable under pressure of the heel to release the hold-down thereby to permit the spring to force the hold-down against the heel.
20. In a heel-seat fitting machine, a heel gage comprising a table for engaging the rim of the attaching face of a heel, a stationary plate constructed and arranged to engage the breast of the heel, a member normally urged toward the plate and movable away from the same under pressure of the heel, and a spring-pressed hold-down for forcing the heel against the table, said member being constructed and arranged to engage the hold-down before the heel has been removed from the gage and to limit movement of the hold-down toward the table.
21. In a heel-seat fitting machine, a heel gage comprising a support for a heel, means for measuring the heel lengthwise upon the support, a spring-pressed hold-down constructed and arranged to force the heel against the support, and a yielding slide constructed and arranged to engage the rear end of the heel and to limit movement of the hold-down under pressure of the spring toward the table when the heel has been moved from the table.
22. In a heel-seat fitting machine, a plate formed and arranged to be positioned between a sole and upper of a shoe, a heel gage comprising a movable abutment, a spiral stop, means including a back gage for positioning the shoe lengthwise relatively to said plate, connections between the stop and the movable abutment to set the stop in accordance with the size of a heel positioned in said gage, means for trimming a chip from the heel-seat portion of the shoe to prepare the shoe for the reception of the heel, a spring-

operated chip ejector movable over the plate to force the chip from the machine, and cushioning means for retarding movement of the ejector under pressure of the spring thereby to prevent the chip from being thrown from the machine.

23. In a heel-seat fitting machine, a plate for supporting the heel-seat portion of a sole, means for reducing the heel-seat portion of the sole, and an ejector bar movable generally lengthwise of said plate for removing material trimmed from the heel-seat portion of the sole from the plate, said bar being mounted for movement about an axis extending generally lengthwise of the plate to permit the bar to follow the sole-engaging surface of the plate.

24. In a heel-seat fitting machine, a plate for engaging the heel-seat portion of the sole of a shoe, means for trimming surplus material from the heel-seat portion of the sole, a chip ejector movable in a path extending over the plate, resilient means for moving the ejector over the plate, and cushioning means for preventing rapid movement of the ejector under pressure of said resilient means thereby to insure that the surplus material is not thrown from the machine.

25. In a heel-seat fitting machine, a plate provided with an opening and constructed and arranged to be positioned between the sole and upper of a shoe, a plunger for cooperating with the plate to distort the heel-seat portion of the sole, means for trimming a U-shaped chip from the margin of said heel-seat portion, an ejector unit slideable lengthwise of the plate, a pivotally mounted arm operably connected to said unit,

a spring for normally retaining the arm in an inoperative position, resilient means, a lever for operating the arm movable forwardly of the plate against the pressure of said resilient means, a latch for temporarily locking the lever against movement under the pressure of said resilient means, a trip member operated by said plunger for moving the latch out of locking engagement with said lever, and a cushioning member connected to said lever and constructed and arranged to prevent the ejector unit from being moved rapidly under pressure of said resilient means.

26. In a heel-seat fitting machine, a plate provided with a U-shaped opening and constructed and arranged to support the heel-seat portion of a sole, means for reducing said heel-seat portion, a carrier movable in a fixed path lengthwise of said opening, a bar supported by the plate and pivotally connected to the carrier to enable the bar to follow a sole-engaging surface of the plate, and means for operating the carrier along said path.

27. In a heel-seat fitting machine, a plate provided with a face constructed and arranged to be engaged by the heel-seat portion of the sole of a shoe, said face being provided with a recess, means for trimming a chip from the heel-seat portion of the sole, a carrier movable in a predetermined path, a chip ejecting bar supported by the plate and pivotally connected to the carrier, said bar being curved to permit the same to enter said recess as the carrier moves in said path, and means for operating the carrier.
